Application July 16, 1931, Serial No. 551,196
Renewed December 20, 1934

2 Claims. (Cl. 60—52)

This invention relates to hydraulic jacks, and the principal object of the invention is to provide a new and improved device of this character.

In the drawings accompanying this specification and forming a part of this application, we have shown, for purposes of illustration, one form which our invention may assume, and in these drawings:

Figure 1 is a side elevational view of an embodiment of the invention.

Figure 2 is an enlarged vertical sectional view of the construction shown in Figure 1.

Figure 3 is a horizontal sectional view corresponding substantially to the line 3—3 of Figure 2.

Figure 4 is a fragmentary vertical sectional view corresponding substantially to the line 4—4 of Figure 3.

Figure 5 is a fragmentary vertical sectional view corresponding substantially to the line 5—5 of Figure 2.

Figure 6 is a fragmentary horizontal sectional view illustrating a modified form of our invention, while

Figure 7 is a view similar to Figure 6, but illustrating a still further modified form of our invention.

The embodiment of the invention herein disclosed comprises an elongated base 10 from which rises a ram cylinder 11 and a reservoir 12, cast integrally with the base 10 and with each other, and having an integrally cast handle 13, the cylinder 11 at its upper end having an interiorly threaded enlargement 14, and at its bottom having a threaded opening closed by a threaded plug 15 having a head 16 fitting in a counterbore 17; and the cylinder 11 and reservoir 12 communicate at their lower ends through a port 18, controlled by a needle valve 19, and adjacent their upper ends communicate through a port 20.

Reciprocably mounted in the cylinder 11 is a tubular ram 21 extending through a ring 22 threaded into the threaded portion of the enlargement 14, extending also through a second ring 23 having threaded engagement with the ring 22, and suitable packing being interposed between the rings 22 and 23. The ram 21 is interiorly threaded at its lower end for the threaded reception of the plug 24 against which bears a packing member 25 held in place by a plate 26 secured in position by screw bolt 27, and the upper end of the ram 21 is also interiorly threaded for the threaded reception of a threaded plug 28, operable to secure to the ram 21 a seat member 100, provided with a lateral extension 29 carrying a downwardly disposed rack member 30 having a tongue and groove slidable bearing 31 between its inner surface and adjacent portion of the outer wall of the cylinder 11, provided along its sides with groove 32 for the

slidable and pivotable reception of pins 33 threaded into the furcations 34 of a seat member 35 having a projection 36 adapted to adjustably engage any one of the rack-teeth 37 disposed along the rack member 30.

One end portion of the casting is enlarged to provide a hollow projection 38, interiorly threaded, as at 39, communicating with a bore 40 in the adjacent portion of the casting; and the bore 40 communicates with a pair of branch bores 10 extending through the casting and constituting pump cylinders 41 and 42, the cylinder 41 communicating with a vertically extending duct 43 leading to the interior of the reservoir 12, having a valve seat for the accommodation of a ball valve 44 held normally closed by a spring 45 bearing upon a supporting plug 46, also communicating with an angularly extending duct 47 having a valve seat for the accommodation of a ball valve 48 held in place by a spring 49 supported by a plug 50, the duct 47 communicating with the lower end of the cylinder 11 through a transverse duct 51. The cylinder 42 communicates with a vertically extending duct 52 leading to the interior of the reservoir 12, having a valve 15 like the ball valve 44, an angularly extending duct 53 having a ball valve 54, and a transverse duct 55 leading to the interior of the cylinder 11, similar to those already described in detail.

Slidably mounted in the cylinder 41 is a piston member 56, its inner end provided with an inverted cup-shaped packing member 51, secured to the end of the piston member 56 by a screw 58. The outer end of the piston member 56 is integrally connected with a cylinder segment 59 working in the bore 40, and provided with a pair of studs 60 for engagement with a pair of closed cam grooves 61 provided in a cylinder cam 62, and the cylinder 42 is provided with a piston member 63 similar to the piston member 56, and having integrally formed therewith a cylinder segment 64 also working in the bore 40 at a point diametrically opposite the cylinder segment 59, and provided with a pair of pins 65 for engagement with the closed cam grooves 61 at a point diametrically opposite the pins 60, the cylinder segments 59 and 64 being positioned to travel in opposite directions when the cylinder cam 62 is rotated. The cylinder cam 62 at its inner end is rotatably disposed in a bearing socket 67, and is provided with a collar 68 bearing against raceways 69 having ball bearings disposed therebetween, accommodated in a cup 70 threaded into the threaded portion of the projection 38; and outwardly of the cup 70 there is provided a packing member 71 held in place by a nut 72. The cylinder cam 62 is provided with a shaft which extends beyond the nut 72, and is provided with a cross pin 73 adapted to be engaged by bayonet 50 55 60 65 70 75 80 85 90 95 100

slots 74 formed in a socket portion 75 of an operating handle 76.

In operation, with the parts in the position as shown in Figure 3, the handle 76 is manipulated 5 to rotate the cylinder cam 62, drawing the piston member 56 therewith, thus creating a partial vacuum in the cylinder 43, unseating the valve 44 and filling the cylinder 43 and duct 47 with fluid, the piston member 63 simultaneously traveling 10 inwardly and driving fluid previously withdrawn from the reservoir in the manner described in connection with the piston member 56 in advance thereof, unseating the valve 54 and discharging the fluid through the duct 55 into the 15 lower end of the cylinder 11. By reason of the fact that the cam grooves 61 are closed or continuous, the continued rotation of the cylinder cam 62, in which the grooves 61 are formed, in either direction will impart reciprocatory motion 20 to the plungers 56 and 63, and these plungers will alternately withdraw fluid from the reservoir and force the same into the cylinder 21 beneath the piston 25. This alternate action of the plungers 56 and 63 causes fluid to be forced into the ram 25 cylinder 21 continuously as long as the cylinder cam 62 is rotated. It will be noted in this connection, that by thus employing a cylinder cam provided with a closed cam groove, the cylinder cam 30 may be rotated continuously in either direction to effect a continuous delivery of fluid under pressure to the ram cylinder. Moreover, this effect may be obtained by oscillating the cam cylinder 62 without making a complete rotation of the same.

35 In Figure 6 of the drawings we have shown the cylinder cam 62 as being provided with but a single closed cam groove 98, which is engaged at diametrically opposed points by pins 76 provided with anti-friction rollers 77. In other respects, 40 the construction shown in Figure 6 is substantially the same as that described in connection with the preceding figures.

In Figure 7 we have shown a still further modified form of our invention, in which we employ but a single plunger 78 provided with a suitable packing 79 at its inner end, and which is mounted for reciprocation within a cylinder 80 communicating at its inner end with a vertical passage 81 opening into the lower portion of the reservoir 12, and with a horizontally extending passage 82 communicating with the interior of the ram cylinder 21 through a passage 83. Backward flow of fluid from the ram cylinder is prevented by means of a ball valve 84 held in engagement with a valve seat 85 adjacent the outer end of the passage 82 by a spring 86. The outer end of the plunger 78 has integrally formed therewith a cylinder cam 87, and this cam and plunger is prevented from rotating by means of a pin 88 carried by the plunger 78 for engagement with a longitudinally 55 extending groove 89 formed in the wall of the cylinder 80. Surrounding the cylinder cam 87 is a rotatable sleeve 90 provided with an inwardly extending pin 91 for engagement with a single closed cam groove 92 provided in the cylinder cam 87. The outer end of the sleeve 90 bears against cooperating race-ways 93 having ball bearings 94 disposed therebetween, and these race-ways are carried by a screw-threaded cup 95 which is threaded into the threaded extension 38 of the main casting. A suitable packing 96 is contained 60 within the extension 38, and is held in position by a screw-threaded ring 97 which is also threaded

into the extension 38. The sleeve 90 is provided with a shaft 98 which extends outwardly through the packing 95 and ring 97 and means by which the sleeve 90 may be rotated. In this particular construction, when the sleeve 90 is rotated, a reciprocatory motion is imparted to the cylinder cam 87 and the plunger 78, which causes fluid to be withdrawn from the reservoir 12 and forced into the ram cylinder through the passages 81, 82, and 83, in a manner hereinbefore described in connection with the structure shown in the preceding figures.

It will be understood by those skilled in the art that the embodiment herein disclosed accomplishes at least the principal object of the invention, that it has uses and advantages other than those herein particularly referred to, and that various changes and modifications may be made without departing from the spirit of the invention, and accordingly, the embodiment disclosed herein is illustrative only, and the invention is not limited thereto.

We claim:

1. A hydraulically operable jack, comprising: a casting providing a reservoir and ram cylinder, and having a normally closed valve controlled passage to effect exhaust of fluid from said ram cylinder to said reservoir; a ram in said ram cylinder; a pump cylinder communicating through ducts in said casting with said ram cylinder and with said reservoir; valve means in said ducts operable to permit one way passage of fluid from said reservoir to said ram cylinder; a piston member in said pump cylinder, movement of which operates said valves; a projecting base portion of said casting; an anti-friction bearing disposed in said projecting portion of said casting; an operating member extending to the exterior of said jack, and rotatably carried by said anti-friction bearing; and cam means extending continuously around one of said members, and a projection carried by the other of said members and engaging said cam means, whereby rotation of said operating member effects reciprocation in opposite directions of said piston member, to thus operate said ram.

2. A hydraulically operable jack, comprising: a casting providing a reservoir and ram cylinder, and having a normally closed valve controlled passage to effect exhaust of fluid from said ram cylinder to said reservoir; a ram in said ram cylinder; a plurality of pump cylinders each communicating through ducts in said casting with said ram cylinder and with said reservoir; valve means in said ducts operable to permit one way passage of fluid from said reservoir to said ram cylinder; a piston member in each of said pump cylinders, movement of which operates said valves; a projecting base portion of said casting; a cup-shaped receptacle threaded into said projecting portion of said casting and containing cooperating race-ways having anti-friction bearings therebetween; an operating member extending to the exterior of said jack, and rotatably carried by said cooperating race-ways; and cam means extending continuously around said operating member, and a projection carried by each of said piston members and engaging said cam means, whereby rotation of said operating member effects reciprocation in opposite directions of said piston members to thus operate said ram.
